[57] CLAIM

The ornamental design for lipstick case or similar article, as shown and described.

DESCRIPTION

FIG. 1 is a perspective view of lipstick case or similar article showing my new design;

FIG. 2 is a front elevational view thereof;

FIG. 3 is a rear elevational view thereof;

FIG. 4 is a side elevational view thereof, the side opposite being a mirror image of the side shown;

FIG. 5 is a top plan view thereof; and

FIG. 6 is a bottom plan view thereof.

Fig. 1
